SCAFFOLD WINCH

Jesse M. Benson, Concord, Tenn., assignor to
 Sasgen Derrick Co., Chicago, Ill., a corporation
 of Illinois

Application October 21, 1946, Serial No. 704,684

1 Claim. (Cl. 254—187)

1

This invention relates to a scaffold hoist and winch, and is an improvement over the construction shown in my pending application Serial No. 670,945, filed May 20, 1946, now Patent No. 2,424,910, granted July 29, 1947, for Safety Scaffold.

An object of this invention is to provide an improved winch construction wherein the winding drum can be manually rotated to either wind or unwind the cable therefrom, and the crank handle can be automatically locked against turning so that the crank handle will not be pulled or jerked from the hand by undue pressure thereon.

Another object of this invention is to provide an improved safety lock for a winch embodying automatically operable clutch means for the driving pinion or gear so as to positively lock the pinion to a ratchet member.

A further object of this invention is to provide a safety winch for a scaffold wherein the winding drum is automatically locked against unwinding and can only be unwound by proportionate rotation of the crank handle, excessive rotation of the drum causing the locking means to become immediately effective so as to thereby relieve the crank handle pressure from the drum.

A further object of this invention is to provide an improved clutch and clutch operator associated with the crank handle so that the crank handle will serve as a brake during the unwinding operation.

With the above and other objects in view, my invention consists in the arrangement, combination and details of construction disclosed in the drawings and specification, and then more particularly pointed out in the appended claim.

In the drawings,

Figure 1 is a detail side elevation, partly in vertical section of a scaffold winch constructed according to an embodiment of this invention, showing the clutch in released position,

Figure 2 is a fragmentary sectional view taken substantially on the line 2—2 of Figure 1, with the clutch in locked or clutching position,

Figure 3 is a sectional view taken on the line 3—3 of Figure 2.

Figure 4 is an end elevation of one of the cam members for actuating the clutch.

Referring to the drawing, the numeral 10 designates generally a frame structure which includes side members 11 and 12 secured together by fastening means 13 and held in spaced apart relation by means of spacer sleeves 14. The frame

2

10 has rotatably mounted therein a winding drum 15 which is carried by a shaft 16 journaled between the sides 11 and 12 of the frame 10. The drum 15 also includes a large spur gear 17 which is fixed relative to the drum and may form one end wall of the winding drum.

The frame 10 also has journaled thereacross a driving shaft 18 which at one end thereof, has pivotally secured thereto a crank handle 19. 10 As shown in Figure 1, the inner end of the shaft 18 is formed with a flattened portion 20 and the adjacent end of the crank handle 19 is bifurcated, as indicated at 21 and pivotally mounted on a pivot member 22 extending through the bifurcations and the flattened portion 20.

The shaft 18 has fixed relative thereto a relatively large diameter clutch plate 23. A ratchet member generally designated as 24 is rotatably mounted on the shaft 18 in confronting position 20 respective to the clutch plate, and in the present instance, the body 25 of the ratchet member 24 constitutes an intermediate clutch plate. The ratchet 24 is adapted to be held against rotation by means of a pivoted dog 26 which is provided 25 at its upper end with a boss or bearing 27 loosely engaging the uppermost of the fastening members 23. The dog 26 gravitatingly engages the teeth of the ratchet 24 and is adapted to be manually swung to a reversed position when in released position.

The spur gear 17 also has engaged therewith a gravity actuated dog 28 also pivotally carried by the uppermost of the fastening members 13. The dog 28 engages the gear 17 on the side opposite from the engagement of the dog 26 with the ratchet 24. A driving pinion or gear 29 is loosely mounted on the shaft 18 and has formed at one end thereof a clutch plate 30 disposed in confronting relation to the clutch plate 25 of the ratchet 24. The pinion 29, at the opposite or inner end 30 thereof has formed thereon cam members 31. The cam members 31 are disposed in confronting relation to complementary cam members 32 which are formed on the inner end of a sleeve 33 which is fixed by means of a pin 34 on the shaft 18.

40 The cam member 31 is constantly urged to rotate the pinion 29 toward clutching position by means of a spiral spring 34' which is fixed at one end as at 35, to the cam 31 and is fixed at the other end, as at 36, to the sleeve 33. The effect of the spring 34' is to partially rotate the driving gear or pinion 29 when the shaft 18 is held stationary so that the pinion 29 will be moved endwise or outwardly to cause the clutch plate 30 to bear 45 against the intermediate clutch plate 25 and to 50 55

cause the intermediate clutch plate 25 to tightly bear against the clutch plate 23 which is fixed to the shaft 18. In this manner, when the ratchet 24 is held against rotation by the dog 26, and the shaft 18 is held against rotation by holding the crank 19, rotation of the pinion 29 by turning of the drum 15 in the direction shown by the arrow 38 will cause the pinion 29 to rotate in the direction of the arrow 37 and the cam members 31 will partially rotate with respect to the cam members 32. The effect of this is to cause the pinion 29 to move endwise to the right, bringing the clutch plates 25 and 23 into tight engagement with each other and as ratchet 24 is held against rotation by the dog 26, the drum 15 is thereby locked against rotation.

The force necessary to hold the shaft 18 against rotation is only a slight force so that the unwinding pressure or pull on the drum 15 will not tend to pull the crank 19 out of the hands of the operator. In order to permit the drum 15 to unwind the cable therefrom, it is necessary that the crank 19 be rotated proportionately therewith in the unwinding direction. This unwinding direction is a counter-clockwise direction and the speed of rotation of the crank 19 will determine the speed of unwinding of the drum 15. In this manner the clutch means hereinbefore described will act with the crank 19 as a releasable brake for releasably holding the drum 15 against rotation in an unwinding direction.

In the event the handle 19 is left free and a pulling strain is placed on the drum 15 causing the cable to unwind therefrom, this pulling strain will tend to rotate the pinion 29 but as this pinion is under the torsional tension of spring 34, the pinion 29 will be caused to be moved relative to the sleeve 33 and the cam members 32 so that the clutch plates will be automatically moved to clutching position. With a winch as hereinbefore described, the workmen on a scaffold will be able to either raise or lower the scaffold to the desired degree and the weight of the scaffold and the articles thereon will have no effect on the unwinding or lowering of the scaffold inasmuch as the clutching means hereinbefore described will be automatically moved to clutching or locking position with respect to the winding drum since the crank handle is held against rotation by the operator or is even left free. This winch will provide a factor of safety for the workmen on the scaffold so that the workmen will not have

to release or lock any part of the winch when winding or unwinding the drum.

What I claim is:

A safety means for the winding drum of a winch comprising front and rear plates, spacing means adapted to hold said plates in spaced apart relation, a winding drum journaled between said front and rear plates, a spur gear forming the front end wall of said winding drum, a drive shaft journaled between said plates above said drum and extending through the front plate, a crank on the extending portion of said shaft, an outer clutch plate fixed to said shaft, a driving gear loose on said shaft and in operative engagement with said spur gear, an inner clutch plate fixed to said driving gear, an intermediate clutch plate between said inner and outer clutch plates and loose on said shaft, ratchet teeth carried by said intermediate clutch plate, a dog pivotally carried by said spacing means engaging said ratchet teeth for normally holding said intermediate clutch plate against rotation in the drum unwinding direction, spiral cam means carried by the inner end of said driving gear, a sleeve fixed on said shaft, spiral cam means carried by said sleeve confronting said first spiral cam means, a contractile clutch operating spring, means securing one end of said spring to the outer side of said first spiral cam means, means securing the other end of said spring to the outer side of said sleeve, said spring constantly urging said first cam means to rotate to clutching position, and a second dog pivotally carried by said spacing means adapted to engage said spur gear whereby an additional safety lock is provided.
